ELECTRICAL STRAIN INSULATOR OR SIMILAR ARTICLE

Fred C. Vose, Severna Park, Md., assignor to General
Electric Company, a corporation of New York

Filed May 18, 1964, Ser. No. 80,024

Term of patent 14 years

(Cl. D26—10)

FIGURE 1 is a perspective view of an electrical strain insulator or similar article showing my new design;

FIGURE 2 is a side elevational view, the opposite side being substantially a mirror image thereof; and

FIGURE 3 is an end elevational view, the opposite end being substantially a mirror image thereof.

I claim:

The ornamental design for an electrical strain insulator or similar article, as shown and described.
